REFINING HYDROCARBON OILS

Application filed June 16, 1928. Serial No. 285,823.

This invention relates to improvements in the manufacture of distilled lubricating oils from petroleum stocks. The invention is of special value and application in the manufacture of distilled lubricating oils from certain types of crude oils or crude oil stocks of which the Gulf coast, south Texas, oils and the California oils may be taken as examples.

In general, lubricating oils may be defined 10 as oils heavier than gas oil, heavier than about 35° Bé., and having viscosities upwards of about 50 at 100° F. Saybolt Universal.

There is a group of constituents, apparently 15 characteristic of naphthalene base crude oils, which are extremely objectionable as components of lubricating oils in particular. These constituents are particularly objectionable in that they render unstable lubricating oils in which they are present. They also impair the 20 quality of lubricating oils containing them in other respects, color for example.

As yet, this group of objectionable constituents has not been definitely identified. These objectionable constituents are themselves 25 apparently of relatively low boiling point, yet they polymerize quite readily to form a tar or tarry substance. This polymerization is promoted, for example, by the presence of air or steam. With certain types 30 of stocks, additional quantities of these objectionable constituents seem to be formed as long as the oil is maintained at elevated temperature, this effect increasing with temperature increase.

A number of schemes of procedure have 35 been proposed intended to avoid the objectionable incidents of the presence of this group of objectionable constituents in lubricating oils, but these proposals have not been entirely satisfactory; in some cases because 40 of operating difficulties and in other cases because of failure to reach the real difficulty.

The present invention provides particularly 45 an improved method of separating constituents of the objectionable group noted above from lubricating oil products produced from stocks containing these objectionable constituents, and the present invention is also useful in other applications, as will appear, 50 in providing an improved method of treat-

ing lubricating oil products with caustic alkali. This invention in one aspect is an improvement upon the operation described in our application filed June 16, 1928, Serial No. 285,820.

According to the present invention, the petroleum stock containing the lubricating oil constituents is subjected to distillation and during the distillation the vapors forming the lubricating oil products when condensed are bubbled through a series of superposed hot alkaline liquid oil baths of progressively increasing alkalinity, and the escaping vapors after passage through the series of baths are condensed to form the distilled lubricating oil products. The constituents of the raw stock suitable as components of the desired lubricating oil products are vaporized therefrom, these vapors are bubbled through the series of hot alkaline liquid oil 60 baths, the vapors being introduced beneath the surface of each of the baths, the oil baths are maintained alkaline by supplying a caustic alkali to the treating bath through which the vapors last pass and overflowing the 65 liquid from this bath to the preceding bath and so on, and vapors including the components of the desired lubricating oil products are taken off from the last hot oil bath. These 70 vapors are condensed without permitting the resulting condensate or condensates to contact with the liquid flowing countercurrent to the vapors through the series of hot oil baths.

In the series of hot alkaline liquid oil baths, 75 the lubricating oil constituents are repeatedly subjected to intimate contact with caustic alkali in generally countercurrent flow. The caustic alkali neutralizes acidic constituents of the oil vapors and, apparently, also acts as a polymerizing agent promoting the polymerization of constituents of the objectionable group noted above. Steam may with advantage be supplied to the treating operation as a distillation medium, and when so supplied also assists in this polymerization 80 and in some cases seems to make the caustic alkali more active. The high boiling constituents not suitable as components of the lubricating oil products including reaction products of the hot alkaline treatment and 85 90 95 100

the products of polymerization of any objectionable constituents present are condensed and, flowing downwardly through the treating baths, are discharged from the lowermost.

5 The vaporization of the raw petroleum stock may be effected in a shell still or a pipe still, for example. The vaporization may be carried out under pressures approximating atmospheric pressure or under sub-atmospheric pressure and with or without the introduction of steam or other hot gaseous medium reducing the partial pressure of the oil vapors. As applied to crude oils, 10 the vapors subjected to the alkaline treatment of the invention may comprise the total vaporized fraction of the crude oil.

The alkaline treatment of the invention is advantageously carried out in a so-called 20 "bubble" tower modified to maintain down-flow therethrough of the oil-alkali mixture or suspension forming the liquid of the several treating baths. The caustic alkali is advantageously supplied to the treatment as 25 a concentrated aqueous solution; the water is evaporated in the treating baths leaving the alkali suspended in the oil forming the baths. The vapors taken off from the last treating bath may with advantage be subjected to a refluxing operation from which 30 separated material is returned to this bath before the vapors are subjected to condensing operations for the condensation of the lubricating oil products. Entrainment of constituents of the hot oil baths may thus be avoided. The vapors taken off from the 35 alkaline treatment may be condensed or fractionally condensed in any convenient apparatus. These vapors may, for example, be 40 passed through a series of towers in which progressively lighter fractions are condensed. As applied to crude oils, the vapors taken off from the neutralization and separation treatment may thus be condensed as 45 a series of distillates, the heavier and more viscous fractions of the series constituting the lubricating oil products.

The invention will be further described in connection with the accompanying drawing 50 which illustrates, diagrammatically and conventionally, one form of apparatus adapted, in conjunction with a suitable still and a suitable fractionating or condensing system for carrying out the invention. It will be 55 understood that the invention can be carried out in other and different forms of apparatus; this particular form is illustrated merely for purposes of exemplification. Any usual form of still and any usual fractionating or condensing system may be used 60 in carrying out the invention and this part of the apparatus is, therefore, not illustrated. In the drawing, Fig. 1 is an elevation of a complete treating tower and Fig. 2 is an 65 enlarged fragmentary section of the same.

Referring to the drawing, in the apparatus illustrated the vapors from the still are supplied through line 1 and are taken off, following the treatment of the invention, through line 2 to the fractionating or condensing apparatus, the vapors passing from line 1 through tower 3 to line 2. The tower 3 is generally of conventional "bubble" tower construction except in the arrangement of the overflow connections from the several plates. 70 Cooling coils 4 and 5 are provided in the upper end of the tower. Line 9 is provided for introduction of steam or other gaseous heating medium into the lower end of the tower. Line 8 is provided for discharge of liquid from the lower end of the tower. Lines 10, 11 and 12 are provided for supplying caustic alkali to one or more of the upper plates in the tower as desired. The tower 3, and the vapor connections between this tower 80 and the still, is with advantage lagged or thermally insulated. The temperature conditions in the tower 3 are controlled by regulating the temperature of the vapors entering through line 1, the circulation of a cooling medium through either or both of the coils 4 and 5 and the introduction of steam or other heating medium through line 9. Oil to be supplied to the still may be used as a cooling medium or some suitable external cooling medium may be so used.

The several plates 13, 14, 15, 16, 17 and 85 18 in the middle section of the tower 3 comprise "bubble" caps 6 adapted to compel the vapors flowing upwardly through the tower to bubble through the liquid on the plates and overflow connections 7. Each overflow connection extends upwardly through the plate to which it is connected to a height appropriate to form a seal maintaining a liquid level submerging the lower edges of the "bubble" caps on the plate. An annular baffle 19 is arranged around the upper end of this extension so that the liquid flowing 90 downwardly through the overflow connection is discharged from the bottom of the liquid bath on the plate instead of from the top as in the usual construction.

In carrying out the invention in the apparatus illustrated, the lubricating oil vapors supplied through line 1 are bubbled successively through the hot liquid oil bath on plate 13, then through that on plate 14, and so on through the tower, caustic alkali is supplied to the bath on plate 10, 11, or 12, the bath liquid is overflowed from the plate to which the caustic alkali is supplied to the next lower plate and so on through the tower, the caustic bottoms are discharged through connection 8, and the lubricating oil vapors after passage through the series of hot alkaline liquid oil baths are taken off through line 2 and separately condensed. The temperature at the lower end of the tower is controlled to maintain in vapor 100 105 110 115 120 125 130

phase all oil constituents suitable as components of the desired lubricating oil products and the temperature at the upper end of the tower is controlled to condense tarry or alkaline or other heavy constituents not suitable as components of the desired lubricating oil products.

The following example will illustrate an operation embodying the invention, as carried out in apparatus of the type illustrated: Gulf coast crude oil is supplied to a small pipe still at a rate of about 400 gallons per hour and discharged from the pipe still at a temperature of about 800° F. After separation of unvaporized residual oil, the vaporized part of the stock is supplied through line 1 to the lower end of tower 3. An aqueous solution of caustic soda, 25° Bé., is supplied through line 11 to the next to the top plate in the tower 3 at a rate slightly exceeding 4 gallons per hour. The temperature at the top of tower 3 is maintained in the neighborhood of 670-690° F. and the temperature at the bottom of the tower in the neighborhood of 690-710° F. Steam superheated to 800-900° F. is supplied through line 9 and a cooling medium is circulated through coil 4 or coil 5 or both coils as required to maintain these temperatures. The vapors escaping through line 2 from the upper end of tower 3 are fractionally condensed to form a heavy lubricating oil, a light lubricating oil and a composite gas oil and naphtha.

Again referring to the drawing, in the apparatus illustrated, the caustic alkali may be supplied to either plate 16, plate 17 or plate 18. By supplying the caustic alkali to one of the lower plates, 16 or 17, the vapors escaping from the bath on the plate to which the caustic alkali is supplied, the last of the treating baths, are subjected to a refluxing operation on the remaining plate or plates.

The operation of the invention provides for prolonged intimate contact between the lubricating oil vapors and the hot alkaline treating liquid with a low pressure drop through the treating operation. In this aspect the invention is particularly advantageous because it avoids deterioration of lubricating oil constituents at the same time that it promotes the effectiveness of the refining treatment, this difficulty being peculiar to lubricating oils because of their relatively high boiling point at any particular pressure and because of their tendency toward decomposition at elevated temperatures. The countercurrent application of the caustic alkali makes the alkali more effective and makes it unnecessary to use more than a small excess of the alkali to effect substantially complete separation of objectionable constituents. Improved fractionation in the treating operation is also obtained in carrying out the invention. This

improved fractionation avoids, in particular, any contamination of the lubricating oil products with high-boiling oil-soluble reaction products of the alkaline treatment.

The invention is particularly adapted to continuous operation, and the control afforded by the invention is of special value in maintaining uniform the distillate products over long periods of operation.

We claim:

1. In the distillation of petroleum stocks for the production of lubricating oils, the improvement which comprises vaporizing from the stock those constituents suitable as components of the desired lubricating oil, passing the vapors containing these constituents successively through a series of hot alkaline liquid oil baths by introduction beneath the surface thereof, supplying caustic alkali to a bath other than the first in the series, passing liquid from this bath to the preceding bath and so on through the series in countercurrent to the vapors, discharging liquid from the first bath in the series, taking off from the last bath in the series the components of the lubricating oil in the vapor state and condensing the same without permitting this condensate to contact as such with the liquid forming the oil baths.

2. In the distillation of petroleum stocks for the production of lubricating oils, the improvement which comprises vaporizing from the stock those constituents suitable as components of the desired lubricating oil, passing the vapors containing these constituents successively through a series of hot alkaline liquid oil baths by introduction beneath the surface thereof, supplying caustic alkali to a bath other than the first in the series, passing liquid from the lower part of the baths to preceding baths in the series in countercurrent to the vapors, discharging liquid from the first bath in the series, taking off from the last bath of the series components of the lubricating oil in the vapor state and condensing the same without permitting this condensate to contact as such with the liquid forming the oil baths.

In witness whereof, we have subscribed our names.

EUGENE C. HERTHEL.
